D11-160.

OR D2,644

EX

Patented

Dec 2,644.

May 7, 1937

Thomas H. Dorian

Design for a Statuette

Photograph
by D. Dutton
B. Moore

The Melodian

United States Patent Office.

THOMAS H. DORIAN, OF WASHINGTON, DISTRICT OF COLUMBIA.

Design No. 2,644, dated May 7, 1867.

DESIGN FOR A STATUETTE.

The Schedule referred to in these Letters Patent and making part of the same.

TO ALL WHOM IT MAY CONCERN:

Be it known that I, THOMAS HAVILAND DORIAN, of the city of Washington, in the county of Washington, and District of Columbia, have originated and designed a new Design for a Piece of Statuary, of which the following is a full, clear, and exact description, reference being had to the accompanying photograph, making part of this specification.

The statue is known as "Shot on the Dead-Line at Andersonville," and represents an emaciated soldier pierced by a bullet for unconsciously leaning his head over the dead-line while reading a letter from his wife. The soldier is represented at the moment of receiving his wound, and is falling, having dropped the coveted letter, A, from his left hand, his blanket from his right hand, (the blanket, B, is just ready to fall from his shoulder,) while with his right hand he tries unsuccessfully, by reason of weakness, to reach the wound in his breast from which the blood is flowing. The left leg is somewhat in advance of the right, as he walked slowly along when he received his death-wound. The clothes are represented as in rags, the head is thrown back, the mouth open, as the exclamation "oh!" escapes from his lips, the eyes rolled back in their sockets, indicating great agony, the general expression of the face having an appalled and startled look.

What I claim as my invention, and desire to secure by Letters Patent, is—

The design for a piece of statuary herein set forth and shown.

Witnesses:

SIMEON H. MERRILL,
R. B. NIXON.

THOS. H. DORIAN.